WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA

CAR COUPLER MECHANISM

Application filed September 27, 1928. Serial No. 308,732.

My invention relates to car coupler mechanism and has for its object to provide means for reliably preventing the locking device by which the outward rotation of the knuckle is normally restrained from accidentally jarring to unlocked position, especially where the means for actuating the lock to cause it to assume unlocked position is the well-known jointed or push-down type of uncoupling lever.

In particular, the invention is primarily concerned with the provision of means for insuring that the device usually employed for locking the coupler lock in locked position shall not be accidentally thrown or jarred to a position releasing the lock from its control.

The uncoupling device which is at present used to a large extent upon freight cars for unlocking car couplers is of the jointed lever or push-down type, the fulcrum or pivot pin about which the lever members turn being so positioned that the parts are only slightly out of balance. It, therefore, results that the inner end of the uncoupling lever may be somewhat easily jarred or jolted upwardly as the car upon which it is mounted moves along the track. If the track is in good condition and the speed of the train is moderate, the upward jarring movements of the inner end of the uncoupling lever device are not of sufficient extent to release the means with which car couplers are commonly provided for preventing the knuckle locking block from accidentally creeping upward to unlocked position. Under circumstances of severe service, however, as for example where the track is in bad condition, the speed is high and freight cars are used in express service, the car bodies are subjected to severe jolting which sometimes results in an accidental upward movement of the inner end of the uncoupling lever sufficiently vigorous to move the means by which the locking block is normally locked against accidental unlocking to a position freeing the latter from the control of said means. If, as is frequently the case, there is little or no pull on the coupler knuckles at the time the locking block

50 is thus accidentally released from the control

of its lock-to-the-lock device, the locking block, not then being clamped between the tail of the knuckle and the side wall of the coupler head, is free to jump upward to lock-set position, thereby permitting the knuckle 55 to perform an uncoupling rotation allowing the train to part. By my invention the car coupler is provided with means for preventing an uncoupling device of the jointed lever type from accidentally causing a releasing 60 movement of the means by which the coupler locking block is normally retained in locked position.

The principal feature of the invention, generally stated, consists in associating with the knuckle locking block a lock lifter member which extends into the coupler head and is adapted to cooperate therewith to prevent an accidental unlocking movement of the lock, the lifter being combined with an uncoupling device of the jointed lever type 70 and being formed with a shoulder normally extending under the top wall of the coupler head to limit accidental uncoupling movement of the lever device, and means extending into the coupler and adapted to be actuated by the uncoupling lever device being provided for preventing said lock lifter from accidentally shifting to a position withdrawing its said shoulder from beneath the upper 75 wall of the coupler head, said means having an angular slot for receiving a portion of said uncoupling lever device.

Other features of the invention relating to special details of construction and advantageous combinations of parts will herein-after appear and be pointed out in the claims.

In the drawings, Figure 1 is a plan view of a car coupler embodying the invention showing its relation to an uncoupling device of the jointed lever type, portions of the car upon which the coupler and its uncoupling device are mounted being also illustrated.

Figure 2 is a front elevational view of the construction shown in Figure 1.

Figure 3 is a view of the car coupler and associated uncoupling device, the view being in side elevation and partly in vertical section and the parts being on normal locked position.

Figure 4 is a fragmentary view, partly in side elevation and partly in vertical section showing the positions assumed by the parts when the lock lifter has been partially raised 5 as a result of an accidental upward movement of the uncoupling lever.

Figure 5 is a view corresponding to Figure 4 but showing the relation of the parts when the locking block has been released from the 10 control of the means by which it is normally locked in locked position.

Figure 6 is a detail elevational view of the lock lifter and the means associated therewith for preventing its accidental actuation 15 by the uncoupling lever.

Figure 7 is a front elevational view of the members shown in Figure 6.

Figure 8 is a sectional view on the line 8—8, Figure 6.

Figure 9 is a sectional view on the line 20 9—9, Figure 6.

In the well-known standard D type coupler, which has been shown in the drawings for the purpose of explaining the invention, 1 indicates the coupler head, 2 is the knuckle pivotally mounted thereon, 3 is the locking block by which outward rotation of the knuckle is normally prevented and 4 is the horizontally rotatable knuckle 25 opener lever that is actuated by the locking block to force the knuckle to open position. These several parts of the coupler may be of standard form but, if desired and as shown in the drawings, the well known 30 standard locking block may advantageously be provided upon its rear side below the slot 5 therein with a bevelled face 6 for cooperating with the forward undercut face 7 of a downwardly projecting lug 8 at the 35 lower end of the lock lifter 9, such construction being fully described in my pending application for Letters Patent of the United States, Serial No. 282,446. It is deemed preferable to provide the lock lifter 9 with the 40 undercut lug at its lower end and to form the locking block 3 with the cooperating bevelled face 6, rather than to strictly adhere to the precise form of the standard locking block, for this construction has been 45 found to be effective in preventing the locking block from accidentally moving to unlocked position under all conditions except where the uncoupling device is of the jointed lever type and then only when the car is 50 subjected to unusually severe jolting due to its passage at high speed over bad track.

Toward its lower end the lock lifter 9 has an upwardly facing shoulder 10 for cooperating with the lower end of the lock-down lug 11 on the interior of the coupler head to lock the lock 3 in locked position. When the parts are in locked position the rear face 12 of the lifter engages the lock-down lug 11 and thus serves to limit rearward movement of the lower end of the

lifter. For slidably and rotatably connecting the lifter to the locking block 3 the lifter is provided near its lower end with oppositely disposed trunnions 13 which operate in shouldered guideways 14 of the locking block 70 in the well-known manner. The movable connection of the lifter to the locking block thus effected permits the shoulder 10 of the lifter to be withdrawn from beneath lockdown lug 11 of the coupler head and enables the locking block 3 to have the swinging movements allowing it to assume lock-set position and to cooperate with the knuckle opener 4 so as to actuate the latter. 75

The lock lifter 9, which projects upwardly 80 through an opening 15 in the top wall of the coupler head, is formed below its upper end with a forwardly extending shoulder 16 which normally stands under the adjacent portion 17 of the top wall of the coupler head when the locking block 3 is in locked position, said shoulder preferably being spaced downwardly a short distance from the overlying wall of the head. The upper end of the lock lifter is provided with 85 a vertically elongated slot or aperture 18 for receiving the end portion 19 of the inner lever member 20 of the uncoupling device of the jointed lever type. 90

Extending downwardly through the opening 15 of the coupler head and lying closely adjacent to the lock lifter 9 is a member 21 which functions as means for preventing the accidental escape of the locking shoulder 16 of the lifter from beneath the overlying portion 17 of the top wall of the coupler head. The lower end of the member 21, which by preventing the withdrawal of the shoulder 16 from beneath the top wall of the coupler head insures that the lock-to-the-lock shoulder 10 at the lower end of the lifter shall not accidentally escape from beneath the lockdown lug of the coupler head, is supported laterally by extending into the slot 5 of the locking block between the lock lifter 9 and the adjacent wall of the lock. It projects into the slot 5 a distance sufficient to enable its lower end to remain in said slot when the lifter 9 is raised to the highest position it may occupy with respect to the lock 3. All danger 105 of the lower end of the lifter locking member 21 escaping from the slot 5 and being supported on the top of the lock so as to prevent the parts from dropping to locked position 110 in the act of coupling is thereby avoided. 115

The member 21 and the upper portion of the lock lifter 9 are preferably of such thickness that when in assembled relation side by side they may extend through the standard size and shape of lock lifter opening 15 in the top wall of the coupler head, thus enabling these parts to be substituted for the usual lifter of the standard D type coupler. In order to afford ample area for resisting wear so as thus to insure long life in service, 120 125 130

the inclined lock-to-the-lock shoulder 10 of the lock lifter is preferably the same width as the combined thickness of the overlapped upper portions of the members 9 and 21; and 5 for a similar reason the shoulder 16 on the lifter which cooperates with the top wall of the coupler head projects laterally from the upper portion of the lifter, as shown in Figure 8, so as to overlap the forward surface 10 of the member 21. The change in thickness of the lock lifter 9 provides an upwardly facing inclined shoulder 22 for cooperating with the lower end of the member 21 to prevent rearward rotation of the latter around 15 the end portion 19 of the inner uncoupling lever member as a center.

The opening 23 at the upper end of the lifter locking member 21 through which the end portion 19 of the inner uncoupling lever member 20 projects is elongated vertically to form a lost motion connection permitting the lock lifter 9 to move upwardly with respect to the member 21 a sufficient distance to bring the shoulder 16 into engagement with 25 the overlying portion 17 of the coupler head while the member 21 remains in substantially its lowest position. The lower portion 24 of the opening 23 is constricted so as closely to embrace the end portion 19 of the uncoupling lever, thus providing a substantially vertical rear shoulder 25 adapted to cooperate with the portion 19 of the uncoupling lever mechanism to resist rearward shifting of the latter when the parts are in normal locked relation. The upper portion of the lever receiving opening 23 is widened as at 26 so as to extend upwardly and rearwardly from its lower constricted portion, the lower rear wall 27 of the wider part being inclined to 30 provide a slope down which the inner end 19 of the uncoupling lever may slide when the latter is released after having been moved by the operator.

When the parts occupy normal locked relation, as shown in Figure 3, the shoulder 16 upon the lock lifter is held in cooperating locking relation to the top wall of the coupler head by means of the lifter locking member 21 whose rear face 28 then stands substantially 45 in contact with the rear wall of the opening 15 in the coupler head. As the member 21 has shouldered engagement at 25 with the portion 19 of the inner uncoupling lever member 20, an accidental rearward movement of the latter tending to withdraw the shoulder 16 from beneath the overlying portion 17 of the coupler head is prevented. Similarly the engagement of the forward face 29 with the forward wall of the opening 15 in the coupler 50 head arrests accidental forward movement of the portion 19 of the uncoupling lever mechanism. Sudden stopping or starting of the train or severe application of brakes to reduce speed thus cannot result in throwing the inner end of the uncoupling lever to a position

affecting the efficient performance of their functions by the members 9 and 21. Downward movement of the member 21 with respect to the coupler head may advantageously be limited by providing said member adjacent 70 its upper end with a laterally projecting lug 30 which rests upon the top wall of the coupler when the parts are in locked position.

The uncoupling device for unlocking the coupler mechanism is of the well known form 75 in which a downward push on the outer end of an outer lever member 31 actuates an inner lever member 20 to cause the free end 19 of the latter to move upwardly. These two lever members, 20 and 31 respectively, are pivotally mounted at 32 upon a bracket 33 secured to the car body, the inner end 34 of the outer lever member extending under the inner lever member 20 so as to be capable of imparting an upward or uncoupling rotation to the latter. 80

The coupler is unlocked by operating the uncoupling lever mechanism in the usual manner except that the operator should move the outer end of the handle or lever member 31 forwardly as it is forced downward. This 90 forward movement, which the normal looseness of the uncoupling lever members on their pivot permits, causes the inner end portion 19 of the inner lever member 20 to move upward and rearward to the extreme upper end of the 95 widened part 26 of the opening 23 in the top of the lifter locking member 21, thus shifting the upper end of the lock lifter 9 a sufficient distance rearwardly to withdraw its shoulder 16 from beneath the overlying portion 17 of the top wall of the coupler head and bring said shoulder into alignment with the slot 15 of the coupler. When the shoulder 16 has thus been retracted from beneath the portion 17 of the coupler head the lock lifter 9 and the 100 member 21 by which it is controlled are free to be raised and the locking block 3 may therefore be caused either to assume lockset position or to execute the extended unlocking movement necessary to rotate the knuckle 105 opener lever for forcing the knuckle to open position.

The mechanism may be assembled by inserting the lock lifter 9 through the throat of the coupler head 1 and then associating the 110 locking block 3 and knuckle 2 with the coupler head in the usual way. When this has been accomplished the locking block 3 is raised to lockset position. This having been done the member 21 is inserted from above 115 through the opening 15 in the top wall of the coupler head, whereupon the portion 19 of the inner uncoupling lever member 20 may be passed through the apertures 18 and 23 respectively formed in the lock lifter 9 and its 120 controlling member 21. The uncoupling device may then be pivotally mounted upon the bracket 33, thus completing the assembly. 125

I claim:

1. In car coupler mechanism, the combina- 130

tion of a coupler head, a rotatable knuckle, a lock for the knuckle, a lock lifter movably connected to said lock and extending upwardly therefrom through the coupler head,
 5 a lifter locking member extending downwardly through the upper wall of the coupler head and cooperating with the latter to prevent accidental movement of said lifter longitudinally of the coupler head, and an uncoupling lever device having an upwardly movable inner end portion extending through and adapted to actuate said lifter member and said lifter locking member, said coupler head being provided on its interior with a
 10 lockdown lug, said lifter member being formed with a shoulder normally projecting under and cooperating with said lug to prevent an accidental unlocking movement of said lock and also being formed with a shoulder adapted to extend under and cooperate with the top wall of the coupler head to prevent the accidental escape of said first named shoulder from beneath said lug, and the upper end portions of said lifter and said lifter locking member being relatively movable to cause said last named shoulder to be withdrawn from beneath said wall.

2. In car coupler mechanism, the combination of a coupler head, a rotatable knuckle, a lock for the knuckle, a lock lifter movably connected to said lock and extending upwardly therefrom through the coupler head, said lock being provided with an upwardly and rearwardly opening slot into which said lifter extends, an uncoupling lever device having an upwardly movable inner end portion extending through and adapted to actuate said lifter, and a lifter locking member extending downwardly through the coupler head and projecting into said slot, said head being provided on its interior with a lockdown lug, said lifter being formed with a plurality of spaced shoulders, one of which is adapted to cooperate with said lug to prevent an accidental unlocking movement of said lock and one of which is adapted to cooperate with the top wall of the coupler head to retain the other shoulder in locking relation to said lug, and said lifter locking member being adapted to cooperate with the coupler head to prevent accidental movement of said lifter to a position permitting an unlocking movement of said lock.

3. In car coupler mechanism, the combination of a coupler head, a rotatable knuckle, a lock for the knuckle, a lock lifter movably connected to said lock and extending upwardly therefrom through the coupler head, an uncoupling lever device having an upwardly movable inner end portion extending through and adapted to actuate said lifter member, said coupler head being formed on its interior with a lockdown lug, said lock lifter being provided with a plurality of rigidly connected spaced shoulders, one of which is adapted

to extend under said lug and the other of which is adapted to cooperate with a portion of the coupler head to prevent withdrawal of said lifter from beneath said lug, and means cooperating with said head for preventing accidental movement of said lifter from normal locked position, said means being adapted to be actuated by said uncoupling lever device.

4. In car coupler mechanism, the combination of a coupler head, a rotatable knuckle, a lock for the knuckle, a lock lifter movably connected to said lock and extending upwardly therefrom through the coupler head, said lifter being provided with an upper shoulder and with a lower shoulder, each of said shoulders being adapted to cooperate with the coupler head and said upper shoulder being adapted to prevent release of said lower shoulder from cooperation with said head, an uncoupling lever device having an upwardly movable inner end portion extending through and adapted to actuate said lifter member, and a lifter locking member for cooperating with said head to retain said upper shoulder in cooperating engagement with said head, said lever device being adapted to cause an initial movement of said lifter independently of said lifter locking member.

5. In car coupler mechanism, the combination of a coupler head, a rotatable knuckle, a lock for the knuckle, a lock lifter movably connected to said lock and extending upwardly therefrom through the coupler head, said lock being provided with a slot for receiving the lower end of said lifter, said head having upon its interior a lockdown lug, said lifter having a lower shoulder adapted to project under said lug to retain said lock in locked position and having an upper shoulder for cooperating with the coupler head to prevent accidental withdrawal of said lower shoulder from beneath said lug, said shoulders being disposed upon opposite sides of said lifter and being rigidly connected, and means cooperating with said lifter and the coupler head for normally retaining said upper shoulder in cooperating relation to said head.

In testimony whereof I affix my signature.

WILLIAM KELSO.
